CARTON

Albert B. Kner, Chicago, Ill., assignor to Container Corporation of America, Chicago, Ill., a corporation of Delaware

Application August 23, 1941, Serial No. 408,117

14 Claims. (Cl. 46—11)

This invention relates to cartons, and more specifically to cartons designed to serve the dual purposes of merchandising or shipping carton for toys such as children's toy automobiles, fire trucks and the like, and a toy garage or building structure adapted for use as a housing for storage of the automobiles or trucks in juvenile play. The invention is illustrated and described herein as applied to a toy garage, but it is not limited to such structures as will become apparent.

One of the principal objects of the invention is to provide an inexpensive yet relatively strong and attractive shipping and merchandising carton made of foldable sheet material such as paperboard so constructed and arranged as to permit it to be used as an adjunct, in play, of the toy merchandise packaged within it, the carton in its preferred form being printed or lithographed on its exterior surfaces to represent the building or other structure into which it is to be transformed and having parts marked and arranged for use as movable, such as windows, doors and the like, or for use as fixed structural parts of the building.

Another object of the invention is to provide a toy building structure, such as a garage, composed of two similarly constructed and printed or lithographed cartons and wherein each carton forms a complementary part of the final structure, the resulting building, if a garage, being adapted to contain or house a plurality of toy automobiles or trucks.

Many other objects, uses and advantages of the invention and numerous modifications or variants of construction and arrangement in accordance therewith will become apparent as the following description is read in conjunction with the drawings.

In the drawings:

Figure 1 is a view of a carton blank according to the invention which has been cut, scored, printed and gummed ready to be folded and secured into container form;

Figure 2 is a perspective view of a carton formed from a blank such as that of Figure 1, showing one end closed and the other in process of being closed;

Figure 3 is a perspective view of a toy garage or the like formed by combining two cartons of the type illustrated in Figure 2, after the same have been opened at their ends and cut and folded in a manner hereinafter disclosed; and

Figure 4 is a perspective view of one carton

when ready to be combined with a second carton in the formation of the building of Figure 3.

The toy garage illustrated in Figure 3 is constructed from two cartons each of which, in turn, may be formed from a blank like the blank of Figure 1. The garage is adapted to receive two automobiles or trucks, one of which may have been packed in one of the two cartons from which the garage is composed and the other in the other. Each of the blanks to be used in forming the composite structure may be printed in a manner and design similar to the other or the blanks may be printed in complementary designs for a particular structure, but various other arrangements may be adopted. In the present instance it will be assumed that the blanks will all be printed alike but in a manner whereby the design and arrangement of one will complement the other so that when the two are put together the resulting structure represents a single toy building of the desired type. The printing preferably includes certain indications and instructions for cutting, folding, etc., so that a child or other person following the instructions may convert the cartons into the desired structure.

The blank of Figure 1 may be formed from a printed sheet and is cut and scored to provide equi-dimensional side wall panels 2 and 4 and what may be termed top and bottom wall panels 3 and 5, respectively, also of equal dimensions, the width of each side wall panel being less than the width of either the top or the bottom panel. Attached along the outer longitudinal edge of the bottom panel 5 is a narrow gummed flap 6 designed to overlap the inside face of the longitudinal marginal edge of side panel 2 and to be secured thereto, the aforesaid panels being differentiated from one another by score lines 7, 8, 9 and 10 which facilitate folding the blank into the carton of Figure 2.

In the carton illustrated, each of the four wall panels is provided with a closure flap at each end. The closure flaps 11, 12, 13, 14, 15 and 16 attached to panels 2, 3 and 4 are to serve as structural parts of the final building and are printed to indicate or represent such parts, the remaining closer flaps 17 and 18 being printed to represent accessories to be cut out or, optionally, to be left unprinted and removed and discarded. However, it is to be understood that all of the closure flaps may be utilized as or to represent structural parts of the building and that, depending upon the purpose, some or all of the closure flaps at one or both ends may be omitted, that is, cut off, in transforming the carton into a toy

building structure. Each part of the carton, therefore, may function first in the carton as a package or container and then as a part of the final toy building structure or as an accessory of the latter.

Preferrably each junction of a closure flap with its body panel is scored in the usual manner, this scoring being indicated by lines 20 and 21. Each of the closure flaps 11 and 12 is of a length equal to the maximum height of the toy building since they are to become center post supports therefore, but as this length is greater than the width of the top and bottom wall panels, such width determining the greatest transverse dimension of the carton, the excess length of each is set off by a score line 22 so that the extreme end portions become tuck ends 22a adapted to be tucked into the carton ends and to lie against the inner face of the opposite side wall panel 4. Each of flaps 11 and 12 is also provided with a pre-formed slit or slot 23 which, preferably, extends along or closely adjacent to the score line 20 or 21, as the case may be, and which, for a purpose later revealed, terminates at its ends substantially predetermined distances from the longitudinal or side edges defining the flaps and the side wall panel 2, while each of flaps 15 and 16, which are each of a length equal to the greatest transverse dimension of the carton, are provided with extension tabs or tongues 24 joined thereto along score lines 25 and adapted to be inserted through slits 23 in closing the carton ends.

The carton blanks may be shipped flat and in the form shown in Fig. 1 or they may have their gummed sealing flaps 6 adhesively secured to the inner faces of panels 2 by folding the blank along score lines 7 and 9. Figure 2 illustrates the manner in which the carton is set up and closed after being filled with the toy automobile or other device for which it is intended. It will be observed that the flaps 13, 14, 17 and 18 are first folded inwardly over the carton ends, followed by flaps 11 and 12 with the tuck ends 22a turned down and tucked into the carton ends against the inner face of panel 4, and, finally, the outer closure flaps 15, 16 are turned over and the tabs or tongues 24 are tucked through the slits 23. The resulting package is both simple and inexpensive yet strong and effective for its first purpose.

The transformation of two cartons into the toy building structure is quite easily effected by observing instructions and diagrammatic illustrations which may be printed on the outer face of panel 5 and on that portion of panel 2 which is adjacent to panel 5, the cartons also having printed lines designating where certain cuts and severances are to be made. After both ends of the carton are opened and the contents removed, the first operation is to cut the panel 2 and the closure flaps 11 and 12 from A to B along the line 26 which may be indicated by scoring or printing or both and which divides the panel and the closure flaps into a relatively narrow strip 2a and a relatively wide strip 2b, the cut also dividing the slits 23 into unequal parts. Following division of the panel 2, notches and cuts at designated places 27 and 28 form tongues 29 and 30, the purpose of which will appear.

As will be explained more fully hereinafter, the narrow strip 2a of one of the pair of complementary and similarly printed cartons is to be interwoven or interlocked with the corresponding narrow strip 2a of the other carton and,

preferably, the arrangement is such that such strips, when interwoven or interlocked, will have their longitudinal edges substantially in register, that is, the free edge of one will be substantially

- 5 in register with the attached edge of the other and vice versa. It is likewise preferable to have the wide strips of the complementary cartons arranged in the same manner. To this end, those portions of slots 23 and the slots 27 all of which 10 extend partly across the narrow strips 2a, should terminate half way between the longitudinal edges defining strips 2a. Similarly the slots 23 and 28 in the wide strips 2b should each extend half way across those strips 2b.
- 15 Printed lines on each of flaps 11 and 12 designate slots 31 to be cut in the narrow strips of these flaps to accommodate the respectively adjacent tongues 32 to be formed on the wide strips of these flaps by cutting along printed lines 32a shown in Figure 1. Each of flaps 11 and 12 should be so cut as to remove those portions bearing the legends "F cut off" and "Cut off F," the removal of these portions preferably leaving the outer end parts of strips 2b, including the 20 tongues 32, of a width substantially equal to the width of the narrow strips 2a. Since the slots or slits 32a preferably extend half way across the remaining width of the wide strips 2b and since the portions marked "F cut off" and "Cut 25 off F" are all of the same width in the sample illustrated, the tongues 32 may be passed through slits 31 to a point where the longitudinal edges of the outer end parts of the narrow and wide strips 2a and 2b will register with one another, all as will develop as the description continues. The flaps 13 and 14 are cut to sever the outer portions thereof along diagonal lines C—D, the tongues 24 are cut to sever those portions thereof which are designated E, and the flaps 30 35 17 and 18 are removed. If desired each of the 40 printed representations of windows shown on panel 4 may be severed about three sides and bent along the fourth side to swing out or in as fancy chooses. The foregoing operations are performed on another carton similar to the first 45 whereupon the two cartons are ready to be put together to provide the structure shown in Figure 3, each carton having the appearance of that shown in Figure 4 if it were folded into form 50 before being joined to the other.

Instead of folding each carton completely into the shape shown in Figure 4, and then putting the two halves of the structure together, it may be preferable to start with the building floor by 55 interconnecting the bottom free edges, that is, the narrow strips 2a of two cartons, with one of tongues 29 overlapping the other and those parts of the strips 2a which are adjacent to and connected with the overlapping tongue 29, underlapping the corresponding parts of the other carton strip 2a. In other words, the strips 2a may be said to be interwoven with one another, the contained portions of slots or slits 23 and slits 27 permitting this to be accomplished. Similarly, the wide strips 2b may be interwoven with one tongue 30 overlapping the opposite tongue 30, as may be observed in Figure 3, the portions of slits 23 contained therein and the slits 28 enabling this to be accomplished. Following the 60 interweaving of the corresponding strips 2a and 2b of the two cartons, the remaining triangular parts of flaps 13 and 14 may be folded down to form gables whereupon the slotted or slotted parts (narrow strip portions) of flaps 11 and 12 are 65 swung upwardly at right angles to the bottom 70 75

or floor of the structure and those parts of flaps 11 and 12 which carry the tongues 32 (wide strip portions) are swung down from the roof to positions overlying the slotted parts and tongues 32 are pushed through the slits to form center posts, after the manner illustrated in Figures 3 and 4. Thereafter, the flaps 15 and 16, which form the doors, are swung across the openings in each end of the building and may be retained in closed position by interlocking the tabs 24 as will be apparent.

It is preferable to bring up the slotted (narrow strip) portions of the flap 11 of one carton and the flap 12 of the other so that they lie together with the slots 31 in register and to bring down the tongue carrying (wide strip) portions of these flaps in overlapping relationship with the tongues 32 in register and to pass the two tongues together through both slots 31, as such an arrangement gives a greater rigidity to the center posts than if each tongue passes through only one slit. Furthermore, it is preferable to tuck the free corners of the gables 13 and 14 in between adjacent portions of the strips forming the center posts as so doing prevents the gables from swinging out of position. The doors also may be retained more securely in closed position if the tab 24 at each end of the structure which has the cutaway portion E along its lower edge is slipped through the slit 31 at that end as may be appreciated. The structure exemplified may readily be converted into other types of building as, for instance, an aeroplane hangar for which purpose it may be preferred to cut off and remove the center post at such end from the lower edges of the gables to the ground and to fasten the free corners of the gables as by a staple or otherwise to support the roof and side walls in proper position.

The toy garage building constructed as hereinabove described will house the toy automobiles or other vehicles purchased in the cartons or may be used for other purposes depending upon the fancy of the user thereof. The doors and windows may be opened and shut and the building may be taken down and reconstructed, as desired. Those portions of flaps 13 and 14 which are to be removed and all of flaps 17 and 18 which are to be wholly removed, may be utilized by printing figures and objects thereon, as illustrated in Figure 1, such figures and objects being adapted to be cut out and utilized in play with the building and toys housed therein.

While the invention has been illustrated and described in connection with a single example, it should be apparent to all skilled in the art that many variations and adaptations of such structure as well as the development of other structures may be readily effected following the teachings hereof. Accordingly, it is not desired to be limited other than by the spirit of the invention and the scope of the appended claims.

I claim:

1. A carton of substantially parallelepiped shape and of the character described comprising, a pair of oppositely disposed rectangular panels forming side walls; a pair of oppositely disposed rectangular panels forming a top wall and a bottom wall, said top and bottom walls being of greater width than the side walls; a closure flap on each of the opposite ends of one of said side walls, each of said side wall closure flaps having a slit along the line of juncture of said side wall and its attached flaps and each slit terminating a predetermined distance from the

opposite free edges of its flap; a closure flap on each end of the other of said side walls adapted to overlie all other closure flaps at its end of the carton, each of such closure flaps having a tucking tongue attached to its outer free edge for insertion into the slit in the opposite side wall end flap at such end of the carton; and a generally rectangular closure flap on each end of another of said walls, each of said last-mentioned flaps having a diagonal cutting line extending from a point on that of its free lateral edges which is adjacent to the side wall flap carrying a tongue outwardly to a point on one of its other free edges.

15 2. A carton of substantially parallelepiped shape and of the character described comprising, a pair of oppositely disposed rectangular panels forming side walls; a pair of oppositely disposed rectangular panels forming a top wall and a bottom wall, said top and bottom walls being of greater width than the side walls; a closure flap on each of the opposite ends of one of said side walls, each of said side wall closure flaps having a slit along the line of juncture of said side wall and its attached flaps and each slit terminating a predetermined distance from the opposite free edges of its flap; a closure flap on each end of the other of said side walls adapted to overlie all other closure flaps at its end of the carton, each of such closure flaps having a tucking tongue attached to its outer free edge for insertion into the slit in the opposite side wall end flap at such end of the carton; a generally rectangular closure flap on each end of said top wall, each of said top wall flaps having a diagonal cutting line extending from a point on that of its free lateral edges which is adjacent to the side wall flap carrying a tongue outwardly to a point on one of its other free edges; and a cutting line extending longitudinally intermediate of the side edges and from end to end of that one of said side walls which carries the slit closure flaps, the last-mentioned cutting line also continuing across said slit closure flaps to the outer ends thereof and dividing the slits.

30 3. A carton of substantially parallelepiped shape and of the character described comprising, a pair of oppositely disposed rectangular panels forming side walls; a pair of oppositely disposed rectangular panels forming a top wall and a bottom wall, said top and bottom walls being of greater width than the side walls; a generally rectangular closure flap at each end of said top wall; a closure flap on each of the opposite ends of one of said side walls, there being a slit through each of said side wall closure flaps along the line of juncture of the flap and its attached side wall and each slit terminating within the bounds of the opposite free edges of its flap; and a closure flap on each end of the other of said side walls adapted to overlie all other closure flaps at its end of the carton, each of such closure flaps having a tucking tongue attached to its outer free edge for insertion into the slit in the correspondingly opposite side wall end flap at such end of the carton, and each of said top wall flaps having a diagonal cutting line extending from a point on that of its free lateral edges which is adjacent to the side wall flap carrying a tongue outwardly to a point on one of its other free edges adjacent to the juncture of such other free edges, there being a cutting line extending longitudinally between the side edges and from end to end of that one of said side walls which carries the slit closure flaps, the last-men-

tioned cutting line also continuing across said slit closure flaps to their outer ends to form divisions thereof and crossing each of said slits between the ends thereof, and the said divisions of each divided closure flap having cutting lines indicating complementary interlocking means.

4. A carton of substantially parallelepiped shape and of the character described comprising, a pair of oppositely disposed rectangular panels forming side walls; a pair of oppositely disposed rectangular panels forming a top wall and a bottom wall, said top and bottom walls being of greater width than the side walls; a generally rectangular closure flap at each end of said top wall; a closure flap on each of the opposite ends of one of said side walls, there being a slit through each of said side wall closure flaps along the line of juncture of the flap and its attached side wall and each slit terminating within the bounds of the opposite free edges of its flap; and a closure flap on each end of the other of said side walls adapted to overlie all other closure flaps at its end of the carton, each of such closure flaps having a tucking tongue attached to its outer free edge for insertion into the slit in the correspondingly opposite side wall end flap at such end of the carton, and each of said top wall flaps having a diagonal cutting line extending from a point on that of its free lateral edges which is adjacent to the side wall flap carrying a tongue to a point on one of its other free edges adjacent to the juncture of such other free edges, there being a cutting line extending between the side edges and from end to end of that one of said side walls which carries the slit closure flaps, the last-mentioned cutting line also continuing across said slit closure flaps to their outer ends to form divisions thereof and dividing each of said slits transversely, the said divisions of each divided closure flap having cutting lines indicating complementary interlocking means, and each of said tucking tongues having cutting lines indicating a part of predetermined interlocking means.

5. A carton of substantially parallelepiped shape and of the character described comprising, a pair of oppositely disposed rectangular panels forming side walls; a pair of oppositely disposed rectangular panels forming a top wall and a bottom wall, said top and bottom walls being of greater width than the side walls; a closure flap on each of the opposite ends of one of said side walls, there being a slit through each of said side wall closure flaps along the line of juncture of the flap and its attached side wall and each slit terminating within the bounds of the opposite free edges of its flap; and a closure flap on each end of the other of said side walls adapted to overlie all other closure flaps at its end of the carton, each of such closure flaps having a tucking tongue attached to its outer free edge for insertion into the slit in the correspondingly opposite side wall end flap at such end of the carton, and there being a cutting line extending longitudinally intermediate of the side edges and from end to end of that one of said side walls which carries the slit closure flaps, the last-mentioned cutting line also continuing across said slit closure flaps to the outer ends thereof and dividing the slits.

6. A carton of substantially parallelepiped shape and of the character described comprising, a pair of oppositely disposed rectangular panels forming side walls; a pair of oppositely disposed rectangular panels forming a top wall and a

bottom wall, said top and bottom walls being of greater width than the side walls; a closure flap on each of the opposite ends of one of said side walls, there being a slit through each of said side wall closure flaps along the line of juncture of the flap and its attached side wall and each slit terminating within the bounds of the opposite free edges of its flap; and a closure flap on each end of the other of said side walls adapted to overlie all other closure flaps at its end of the carton, each of such closure flaps having a tucking tongue attached to its outer free edge for insertion into the slit in the opposite side wall end flap at such end of the carton, there being a cutting line extending longitudinally between the side edges and from end to end of that one of said side walls which carries the slit closure flaps, the last-mentioned cutting line also continuing across said slit closure flaps to their outer ends to form divisions thereof and crossing each of said slits between the ends thereof, and the said divisions of each divided closure flap having cutting lines indicating complementary interlocking means.

7. A blank adapted to be folded into a carton of substantially parallelepiped shape and of the character described comprising, a pair of rectangular panels forming side walls; a pair of rectangular panels forming a top wall and a bottom wall alternating with said side walls, said top and bottom walls being of greater width than the side walls; a closure flap on one end of one of said side walls, there being a slit through said side wall closure flap along the line of juncture of the flap and its attached side wall, said slit terminating a predetermined distance from free edges of its flap; and a closure flap on the other side wall at the same end of the blank adapted to overlie the first-mentioned closure flap and having a tucking tongue attached to its outer free edge for insertion into the slit in the opposite side wall end flap when the blank is folded into carton form, said blank having a cutting line indicated longitudinally and intermediate the sides of the first-mentioned side wall and extended to the free terminal end of the flap attached thereto for division of said flap into two parts, one of said flap parts having an indicated slit and the other an indicated tongue adapted to be interlocked together.

8. A blank adapted to be folded into a carton of substantially parallelepiped shape and of the character described comprising, a pair of rectangular panels adapted to form side walls alternating with a pair of rectangular panels adapted to form a top wall and a bottom wall, said top and bottom walls being of greater width than the side walls; a closure flap on one end of one of said side walls, there being a slit through said side wall closure flap along the line of juncture of the flap and its attached side wall, said slit terminating a predetermined distance from the opposite free edges of its flap; and a closure flap on the other side wall at the end thereof that is on the same side of the blank as the first-mentioned flap having a tucking tongue attached to its outer free edge for insertion into the slit in the opposite side wall end flap when the blank is folded into carton form, there being an indicated cutting line extending longitudinally of the first-mentioned side wall and across said slit flap to the outer free end thereof dividing such wall and flap into two parts, one of such parts of the flap having an indicated slit and the other part having an indicated tongue, the first-mentioned

side wall having indicated cutting lines at each side of said longitudinal cutting line for the formation of means to interlock with complementary parts of another blank.

9. A toy building constructed from two cartons each of which is of the character of the carton described in claim 5, each of said cartons having been cut along said cutting line, one pair of correspondingly similar cut edges of the cartons being secured together to provide a roof, the other pair of correspondingly cut edges of the cartons being secured together to form a floor spaced from the roof, one pair of correspondingly similar divisions of the slit closure flaps depending from the roof at one end of the structure and the other pair of correspondingly similar divisions of the slit closure flaps upstanding from the floor at the same end of the structure and secured to the depending pair of flap divisions thereat whereby to form a post extending from the roof to the floor.

10. A toy building constructed from two cartons each of which is of the character of the carton described in claim 3, each of said cartons having been cut along said cutting line, one pair of correspondingly similar cut edges of the cartons being secured together to provide a roof, the other pair of correspondingly cut edges of the cartons being secured together to form a floor spaced from the roof, one pair of correspondingly similar divisions of the slit closure flaps depending from the roof at one end of the structure and the other pair of correspondingly similar divisions of the slit closure flaps upstanding from the floor at the same end of the structure and secured to the depending pair of flap divisions thereat whereby to form a post extending from the roof to the floor, the remaining parts of the top wall closure flaps, when the same have been cut along said diagonal cutting lines, forming gables.

11. A toy building constructed from two similar tubular cartons each of which is of parallelepiped form, one of the sides of each carton being divided into two parts by cutting the same longitudinally, each of the parts of the cut side of one carton being joined to the corresponding part of the cut side of the other carton to provide an enclosing structure having substantially twice the volume of either individual carton, each of said cartons having building structural features printed thereon in an arrangement whereby to mate with the other carton in the semblance of a predetermined type of building.

12. A toy building constructed from two similar tubular cartons each of which is of parallelepiped form, one of the sides of each carton being divided into two parts by cutting the same longitudinally, each of the parts of the cut side of one carton being joined to the corresponding part of the cut side of the other carton to provide an enclosing structure having substantially twice the volume of either individual carton, each of said cartons having building structural features printed thereon in an arrangement whereby to mate with the other carton in the semblance of a predetermined type of building.

13. A toy building constructed from two similar tubular cartons each of which is of parallelepiped form, one of the sides of each carton being divided into two parts by cutting the same longitudinally, each of the parts of the cut side of one carton being joined to the corresponding part of the cut side of the other carton to provide an enclosing structure having substantially twice the volume of either individual carton, each of said cartons having building structural features printed thereon in an arrangement whereby to mate with the other carton in the semblance of a predetermined structure, at least one of said cartons having a closure flap at one end, said closure flap being printed to represent a building structural unit.

14. A toy building constructed from two similar tubular cartons each of which is of parallelepiped form, one of the sides of each carton being divided into two parts by cutting the same longitudinally, each of the parts of the cut side of one carton being joined to the corresponding part of the cut side of the other carton to provide an enclosing structure having substantially twice the volume of either individual carton, each of said cartons having building structural features printed thereon in an arrangement whereby to mate with the other carton in the semblance of a predetermined structure, said one side of each carton having a closure flap at one end thereof and which flap is also divided by cutting the same as a continuation of said cutting of said one side, and means for interlocking said flap divisions together across one end of the structure provided by the combined cartons.

15. A toy building constructed from two similarly dimensioned cartons each of which is of substantially parallelepiped form and has one pair of substantially opposite sides of substantially equal dimensions and another pair of substantially opposite sides of substantially equal dimensions, one pair of said sides being of lesser width than the width of the other said pair, one of the lesser width sides of one carton having a closure flap thereon at one of its ends, the corresponding lesser side of the other carton having a closure flap thereon at its opposite end, said one lesser width side and the flap thereon of each carton being divided longitudinally thereof into two strips, the correspondingly similar division edges of the two cartons being joined together with one carton rotated end for end through 180° in a horizontal plane with respect to the other, the corresponding strips of the said divided flaps being at one end of the structure and arranged to overlap one another, and means securing said divided flaps in overlapped relationship.

ALBERT B. KNER.
